REFRIGERATED DISPLAY CASE

Harry A. Morris, Trenton, N. J., assignor to C. V. Hill & Company, Inc., Trenton, N. J., a corporation of New Jersey

Application August 15, 1951, Serial No. 241,956

7 Claims. (Cl. 62—89.5)

1

This invention relates to display cases adapted for use in self service stores and which for this purpose are open at the top for access to customers.

It is common practice to provide an open self service display case with a blower for circulating the air upward through an article supporting rack and about the articles in a display space to maintain them in a cool refrigerated condition. The air thus circulated is drawn off the top of the display space and returns to the refrigerated coils for recooling and recirculation. However, when the articles on display are arranged close together in the display space it is frequently difficult or impossible for the air to circulate sufficiently freely about the articles to insure uniform refrigeration thereof. In such cases the lower articles near the source of the cool air remain fresh and refrigerated while the upper articles may spoil from lack of refrigeration. Furthermore, if articles are removed from one end of a display case while they remain closely packed near the other end of the case the air will naturally flow toward the open portion of the case causing uneven refrigeration of the articles on display.

In accordance with the present invention these objections to constructions of the prior art are overcome by providing a refrigerated display case with alternative air circulating channels whereby the air may be circulated in the normal manner upward through and about the articles on display when the articles are spaced sufficiently to avoid interference with the air circulation. However, in the event, the articles are closely packed in a manner to obstruct normal circulation, the refrigerated air will flow through an alternative passage into the upper portion of the display area so as to cascade downward over and about the articles on display insuring proper refrigeration thereof under all conditions of use.

The advantages of the present invention are preferably attained by providing air circulating passages leading from the refrigerated coils to the space beneath a perforated article supporting rack. However, an alternative air duct is arranged so as to communicate with the space below the article supporting rack and leading to openings above the normal level of articles in the display space but well below the top of the case. With this construction, when the apertures in the article rack are obstructed the refrigerated air will flow through the alternative passageway and be discharged into display space above the articles and insure proper cooling thereof. More-

2

over, when one end of the case is closely packed, while the other end is sparsely filled, the case provides for alternative cold air circulation whereby air will flow up through the article supporting rack to cool the items in the sparsely filled area while at the same time refrigerated air will flow downward over the closely packed objects in the other end of the case.

Accordingly, it is a general object of the present invention to provide a refrigerated display case with alternative air circulating passages which insure adequate refrigeration of articles on display regardless of the position or quantity of merchandise in the case.

10 Another object of the present invention is to insure continuous and adequate refrigeration of articles on display in an open type refrigerated display case without necessarily maintaining identical air circulation in all parts of the display space.

15 These and other objects and advantages of the present construction will appear to those skilled in the art from the following description of a typical embodiment of the invention.

20 25 In the drawings:

Fig. 1 is a perspective of a typical display case embodying the present invention with parts thereof broken away;

Fig. 2 is a sectional view showing a portion of an alternative air circulating passage;

30 Fig. 3 is a sectional view of the construction illustrated in Fig. 1 showing normal air flow when the case is loosely packed; and

Fig. 4 is a sectional view similar to Fig. 3 showing air circulation when the case is closely packed.

35 In that form of the invention chosen for purposes of illustration in the drawing the display case embodies an insulated rear wall 3, an insulated bottom 5, insulated end walls 7 and an insulated front 17. The front, rear and end walls cooperate with the bottom of the case to define a display space 25 which is open at the top for access to customers.

A baffle is arranged with its upper portion 9 spaced from the rear wall 3 to form an air circulating duct 20 provided with air inlet openings 18 located at or slightly below the level of the front and end walls of the case. The lower portion of the baffle projects forward as shown to provide chambers 23 located on opposite sides of a fan housing 19. Refrigerating coils 22 are arranged within the chambers 23 and communicate with the fan housing through the lower rear portion thereof so that air will be drawn off from the upper portion of the display space to enter

the upper end of the air duct and circulate downward over the coils 22 and to the fan housing 19. From the fan housing the air is expelled through the outlet opening 4 adjacent the bottom of the display case and beneath an air deflecting and distributing plate 6. In the preferred construction shown the bottom of the case is provided on its upper face with a plate coil 8 consisting of refrigerant carrying coils welded to a floor plate to further cool the air as it spreads out prior to flowing upward through the display space.

Within the lower portion of the display space there is located a perforated article supporting the rack 10 which is spaced from the bottom of the case so as to define an air distributing chamber 27. Air issuing from the fan housing through the outlet 4 will therefore be caused to spread out through chamber 27 and issue through the openings in the perforated article supporting rack 10 to enter the display space and flow substantially uniformly upward therethrough.

During the normal operation of the display case when articles are relatively sparsely distributed on the article supporting rack 10, air will circulate upward through the rack 10 about the articles as shown in Fig. 3 returning to the inlet ports 18 at the upper end of the air duct 20. It will then flow downward again through air duct 20 so that the air will be cooled and circulated in a manner to insure adequate refrigeration of the articles on display.

In order to provide for that condition frequently encountered wherein the articles are arranged on the article supporting rack 10 so closely together as to obstruct the flow of air upward through the article supporting rack, the present invention provides an alternative air circulating passage 14 which has inlet openings 12 communicating with the air distributing chamber 27 beneath the article supporting rack 10 in the lower portion of the display case. The passage 14 extends upward adjacent the lower portion 11 of the rear baffle defining the coil chamber 23 so that the air is further chilled. It then continues to flow upward adjacent the portion 9 of the rear baffle and issues from ports 16 located above the normal level of the articles on display, but well below the top of the display case.

With this construction when the display space is well packed with merchandise or the openings in the article supporting rack are obstructed for any other reason, air cooled by the refrigerated coils 22 will issue into the air distributing chamber 27 through the outlet opening 4 near the bottom of the fan housing and will cool the articles in contact with the rack. Thereafter finding its upward flow through rack 10 impeded it will flow through the inlet ports 12 and the alternative passage 14 to the outlet opening 16. The air will be further cooled in passage 14 by heat exchange with the refrigerating means in coil chamber 23 so that when it flows forward from opening 16 it will cascade downward over and about the articles in the display space to refrigerate them from above. After absorbing heat from the articles on display the air will rise and return to the rear air duct 20 through the upper inlet openings 18.

In order further to avoid interference and eddy currents between the cold air issuing from ports 16 and the relatively warmer air returning to the inlet ports 18 at the upper end of air duct 20 a deflector 13 is positioned above the outlet openings 16 to deflect the air from the alternative

passage forward and downward toward the display space 25.

In many instances, the articles supported on the rack 10 are spaced apart differently in one portion of the display space than in another so that both types of air circulation, namely that shown in Fig. 3 and that shown in Fig. 4, may take place simultaneously in different portions of the display space so as to insure adequate refrigeration of the articles on display under all conditions of use and arrangement. Furthermore, when the air is circulated as illustrated in Fig. 4, the closely packed articles in the display space are not only refrigerated by the air cascading down onto the upward surfaces of the goods, but they are further refrigerated by their contact with the air seeping upward through and about the articles adjacent the article supporting rack 10 whereby the articles on display even when closely packed as shown in Fig. 4 will be directly refrigerated at all times. Thereafter as articles are removed by customers in the normal course of business in self service stores, the type of circulation will change automatically from that of Fig. 4 to that of Fig. 3 without attention on the part of any attendant and as required by conditions when they occur to provide the most effective type of refrigeration consistent with the arrangement of merchandise in the display space.

It will be apparent from the foregoing description that the position and arrangement of the air circulating air duct 20 and the alternative air circulative passage 14 and of their inlet and outlet openings may be varied considerably depending upon the style and type of the display. In view thereof, it should be understood that the particular embodiment of the invention shown in the drawing is intended to be illustrative only and is not intended to limit the scope of the invention.

I claim:

1. A refrigerated display case having a display space closed about its sides and at the bottom but being open at the top for access to the customers, said display case being provided with an air circulating duct having inlet openings communicating with said display space near the top of the case, said case having refrigerating means in heat exchanging relation with air circulated through said duct, a fan operable to circulate air downward through said duct and serving to discharge said air from the duct into the bottom of the display case, said case having a secondary air circulating passage communicating with the lower portion of said case and having discharge openings located at a point above the normal level of articles in said display space but well below the top of said case.

2. A refrigerated display case having a display space closed about its sides and at the bottom but open at the top for access to customers, a perforated article supporting rack located in said display space and spaced from the bottom of the case so as to cooperate therewith to form an air distributing chamber, an air duct having inlet openings communicating with the display space near the top of the case and having a discharge opening communicating with said air distributing chamber, a blower positioned to circulate air through said duct and into said chamber, refrigerating means positioned in heat exchanging relation with the air thus circulated, and an alternative air duct communicating at its lower end with said chamber and having outlet openings

located at a point above the normal level of articles in said display space but well below the top of said case to discharge air into the display case when the perforations in said article supporting rack are obstructed with merchandise.

3. A refrigerated display case having a display space closed about its sides and at the bottom but open at the top for access to customers, a perforated article supporting rack located in said display space and spaced from the bottom of the case so as to cooperate therewith to form an air distributing chamber, an air duct extending downward adjacent the rear wall of the case and having inlet openings communicating with the display space near the top of the case and having a discharge opening communicating with said air distributing chamber, a blower positioned to circulate air through said duct and into said chamber, refrigerating means located in said air duct to cool the air thus circulated, and an alternative air duct communicating at its lower end with said chamber and having outlet openings located at a point above the normal level of articles in said display space but well below the top of said case to discharge air into the display case when the perforations in said article supporting rack are obstructed with merchandise.

4. A refrigerated display case having a display space closed about its sides and at the bottom but open at the top for access to customers, a perforated article supporting rack located in said display space and spaced from the bottom of the case so as to cooperate therewith to form an air distributing chamber, an air duct having inlet openings communicating with the display space near the top of the case and having a discharge opening communicating with said air distributing chamber, a blower positioned to circulate air through said duct and into said chamber, refrigerating means positioned in heat exchanging relation with the air thus circulated, and an alternative air duct communicating at its lower end with said chamber and having outlet openings located at a point above the normal level of articles in said display space but well below the top of said case to discharge air into the display case when the perforations in said article supporting rack are obstructed with merchandise, said alternative air duct being arranged in heat exchanging relation with said refrigerating means so as to further cool the air on its passage through said alternative duct.

5. A refrigerated display case having a display space closed about its sides and at the bottom but open at the top for access to customers, a perforated article supporting rack located in said display space and spaced from the bottom of the case so as to cooperate therewith to form an air distributing chamber, additional refrigerating means on the upper surface of the bottom of the case to cool air within the air distributing chamber, an air duct having inlet openings communicating with the display space near the top of the case and having a discharge opening communicating with said air distributing chamber, a blower positioned to circulate air through said duct and into said chamber, refrigerating means positioned in heat exchanging relation with the air thus circulated, and an alternative air duct

communicating at its lower end with said chamber and having outlet openings located at a point above the normal level of articles in said display space but well below the top of said case to discharge air into the display case when the perforations in said article supporting rack are obstructed with merchandise.

6. A refrigerated display case having a display space closed about its sides and at the bottom but open at the top for access to customers, a perforated article supporting rack located in said display space and spaced from the bottom of the case so as to cooperate therewith to form an air distributing chamber, an air duct having inlet openings communicating with the display space near the top of the case and having a discharge opening communicating with said air distributing chamber, a blower positioned to circulate air through said duct and into said chamber, refrigerating means positioned in heat exchanging relation with the air thus circulated, and an alternative air duct communicating at its lower end with said chamber and having outlet openings located at a point above the normal level of articles in said display space but well below the top of said case to discharge air into the display case when the perforations in said article supporting rack are obstructed with merchandise, said alternative air duct being arranged in heat exchanging relation with said refrigerating means so as to further cool the air on its passage through said alternative duct, and air deflecting means located above the outlet openings of said alternative air duct for separating the air issuing therefrom from air returning to the inlet openings near the top of the case.

7. A refrigerated display case having a display space which is closed about the sides and at its bottom but open at the top for access to customers, a perforated article supporting rack spaced from the bottom of the case and cooperating therewith to form an air distributing chamber, a baffle member spaced from the rear wall of the case and cooperating therewith to form an air duct with an inlet opening communicating with the display space near the top of the case, refrigerating means located in said air duct, a fan housing communicating with the lower portion of said air duct and having a discharge opening communicating with said air distributing chamber, a fan in said housing for drawing air into said air duct through said inlet opening and causing it to flow over the refrigerating means to said air distributing chamber, a second baffle member extending generally parallel to the first mentioned baffle member forming an alternative air duct communicating at its lower end with said air distributing chamber and provided at its upper end with air outlet openings located above the normal level of merchandise on said article supporting rack but well below the top of the case.
